UNITED STATES PATENT OFFICE

2,577,495

LOCOMOTIVE PILOT AND COUPLER
THEREFORHarry H. Wolfe, Columbus, Ohio, assignor to The
Buckeye Steel Castings Company, Columbus,
Ohio

Application October 16, 1947, Serial No. 780,227

11 Claims. (Cl. 213—6)

1

This invention relates to locomotive pilots and couplers, and more particularly to a novel pilot, retractable coupler and pilot doors.

There are quite a number of locomotives which have cast steel pilots at the front end into which horizontally retracting couplers are fitted. In general, such structures include a pilot door with a pocket integral with the pilot and into which the coupler is fitted. The door and coupler pivot about the same vertical axis. In such a structure, the door projects beyond the face of the pilot on the left side and there is a large opening in the pilot at the right side of the coupler. When an opposing coupler mismates (does not couple on impact) with the retractable coupler, such opposing coupler may slip by on the knuckle side of the retractable coupler and hit the forwardly extending pilot door, resulting in damage thereto which may render the structure inoperative.

The primary object of the present invention is to eliminate this disadvantage in the prior device and to provide an arrangement in which the pilot doors provide a smooth pilot front with the coupler retracted and which close the openings, except for that required for coupler movement, when the coupler is in an operating position.

Another object is to provide a structure of this character in which the coupler is the only projecting element when the coupler is in the operating position.

Other objects and features of the invention pertain to the organization and the structural elements as hereinafter described in detail, and further objects and features of the invention will be more apparent as the present disclosure proceeds, and upon consideration of the accompanying drawings wherein a typical embodiment of the invention is illustrated.

In the drawings:

Fig. 1 is a top plan view of my construction, partially in transverse horizontal section, taken on the line 1—1 of Fig. 2, and with the coupler in an operating position.

Fig. 2 is a front elevational view with the coupler retracted.

Fig. 3 is a side elevational view with the parts positioned as indicated in Fig. 2.

Fig. 4 is a longitudinal vertical sectional view on the line 4—4 of Fig. 1.

Fig. 5 is a top plan view of the main pilot door.

Fig. 6 is a vertical sectional view of the same taken on the line 6—6 of Fig. 5, and illustrating the door latch.

2

Fig. 7 is a view similar to Fig. 6 but taken on the line 7—7 of Fig. 5, and showing a sliding abutment which cooperates with the latch to limit swivelling of the coupler when the latter is in operating position.

Fig. 8 is a rear elevation of the pilot door.

Fig. 9 is a horizontal sectional view of a detail taken on the line 9—9 of Fig. 7, and showing the relation of the sliding abutment to the latch pin.

Fig. 10 is a top plan view of the main door retainer and coupler carrier.

Fig. 11 is a front elevation of the same.

Fig. 12 is a vertical sectional view taken on the line 12—12 of Fig. 11.

Fig. 13 is an enlarged fragmentary horizontal sectional view of a portion of the door structure and a buffing surface on the pilot structure.

Referring to the drawings, 1 designates a cast steel pilot which may be bolted to, or cast integral with, a conventional pilot beam 2. The coupler, indicated generally by the reference character 3, has a shank 4 provided with upwardly and downwardly extended cylindrical bosses 5 which fit between co-axial bosses 6 of the pilot 1. The bosses 6 extend, respectively, upwardly and downwardly from the floor 6a and roof 6b of the pilot structure. A pocket 14 is provided within the pilot structure.

30 A vertical pivot pin 7 extends through the bosses of the pilot and coupler and connects the coupler to the pilot.

A main pilot door 8 is provided at its rear side with a parti-cylindrical channel 9, the axis of which is concentric with the axis of the pin 7 and such channel receives the parti-cylindrical inner end of the shank of the coupler, which inner end includes the bosses 5, whereby buffing forces applied to the coupler will be transmitted directly to the door when the coupler is in the operating position.

45 A door retainer 10, designed to pivotally connect the lower boss 5 of the coupler with the pilot door, is secured to the door by any suitable means,

such as bolts 11, and it will be noted the retainer lies under the coupler and has an extension or shelf 12 on which the coupler shank slides when swivelling. The extension 12, in turn, rests on a boss 13 integral with the floor 6a of the pocket 14. When the door retainer is secured to the door 8, they pivot together about the lower boss 5 on the coupler shank and are supported on boss 13 on the pilot.

50 The door 8 has a forward projection 15 with an arcuate face 16. The latter is symmetrical about

the horizontal center line of the coupler 3 so in case of a rear end collision with the coupler retracted, said face will strike the opposing knuckle (not shown) and will tend to prevent the locomotive from lifting the rear car, due to the inclined face of the pilot.

From Fig. 1, it will be noted that a face 11 on the pilot is made with a radius R which is eccentric with respect to the center of the pin 7, whereby when the coupler is moved to the operating position and the projection 15 turns in a clockwise direction, face 16 will contact a complementary face 17 of the pilot at about the time a latch pin 18 enters recess 19 in the boss 13 of the pilot. In other words the convex face 16 on the door structure 8 and the concave buffering surface 17 carried by the pilot structure are both struck about a center which is laterally displaced from the axis of the pin 7 as indicated by the arrow 40 in Fig. 1. Thus, close contact of the faces 16 and 17 is obtained, and pin 7 is relieved of any buffering forces. The part of the pilot forming the face 17 is recessed at 25 to accommodate a portion of the guard arm 35 of the coupler 3 when the coupler is in the retracted position, as indicated in dot and dash lines in Fig. 1.

At the right side of the main door 8, is an auxiliary door 20 which is hinged to the front of the pilot and closes the opening 20a required to retract the coupler. This door is open only when the coupler is being moved into or out of the operating position.

At the left side of the main door 8, is another auxiliary door 21 which is hinged to the front of the pilot and closes the recess or cavity 22 which is provided for the air and signal lines (not shown).

Both auxiliary doors are provided, respectively, with conventional latches 23 and 24 which cooperate with the opposite sides of the main door to hold the doors 20 and 21 in closed positions. It will be noted that the door 20 conceals and protects hand lever 26 of latch pin 18, when the coupler is retracted, and door 21 conceals said lever when the coupler is in the operating position, except when the air and signal lines are in use, at which time door 21 remains open.

Referring to Fig. 6, it will be noted that the latch pin 18 is slideable vertically in the door 8, and it is manually controlled by the lever 26, pivotally connected at 27 to the door for movement about a horizontal axis. A spring 28 is arranged between the top of the pin and a stationary portion of the door to yieldingly move the pin downwardly and keep it from bouncing.

With reference to Figs. 7 and 9, it will be noted that a wall 29 which forms an extension of the channel 9 at one side of the door, is provided with a vertical slot 30 to accommodate upward and downward movement of an abutment or block 31 which has a T-shaped appendage 32 extended through the slot and engageable with a lug 33 of the latch pin 18. The abutment or block 31 is raised by said lug 33 but does not necessarily drop as pin 18 drops. When the coupler 3 is in the operating position, its swivel toward the door 21 is limited by the abutment or block 31, and its movement toward the opposite side is limited by a wall 34, also forming an extension of the channel 9. When the coupler is to be retracted, the pin 18 is raised by the latch lever 26, and as the door and coupler swing toward the retracted position, the pin 18 rides on the boss 13 of the pilot. When the guard arm 35 of the coupler enters the recess 25 on the pilot,

the swivel of the coupler is limited and the coupler shank moves under the abutment or block 31 before the pin 18 drops into the recess 19 in the boss of the pilot. This arrangement provides additional swivel of the coupler in the retracted position and permits more bearing contact between faces 16 and 17 when the coupler is in the operating position.

When the coupler is moved into the operating position, it must be centered to couple, at which time, block 31 drops to its lower position and restricts the swivel of the coupler while in the operating position.

From the foregoing, it will be recognized that I have provided

1. A pilot which has a smooth face when the coupler is in the retracted position.

2. A pilot door arrangement that does not protrude beyond the face of the pilot when the coupler is in the operating position.

3. A main pilot door which will tend to prevent the locomotive from lifting the rear car due to the inclined pilot face in case of a rear end collision.

4. A pilot door which transmits the buffering forces from the coupler to the pilot. The swivel pin is relieved of buffering forces and takes only the pulling forces.

5. A pilot door auxiliary which limits the swivel of the coupler when in the open position but provides additional swivel to one side when the coupler is retracted.

From the foregoing, it is believed the construction, operation and advantages of my improved construction may be readily understood, and it is apparent that changes may be made in the details disclosed without departing from the spirit of the invention, as expressed in the following claims:

What I claim and desire to secure by Letters

40 Patent is:

1. In a coupler and pilot organization for a locomotive, a coupler including a shank, a pilot, vertically aligned bosses on the pilot, a vertically disposed pivot pin extending through the coupler shank into said bosses so that the coupler may be turned about the axis of the pin, a door structure abutting a rear end of the coupler shank mounted to turn about the axis of said pin with the coupler, a projection carried by the door structure arranged generally diametrically opposite the coupler shank, an arcuate end face on the projection generated about a vertical axis laterally displaced with respect to the center of said pivot pin, an arcuate buffering surface carried

55 by the pilot struck about a vertical axis laterally displaced with respect to the center of the pivot pin whereby the end face of the projection is wedged into engagement with said buffering surface when the coupler is turned to an operative position to relieve the pivot pin of buffering forces in the application of pushing strains on the coupler.

2. In a coupler and pilot assembly, a coupler having a shank, a pilot, means including a vertically disposed pivot pin connecting the coupler shank to the pilot so that the coupler may be turned in a horizontal plane, a fixed arcuate buffering surface carried by the pilot struck about a vertical axis displaced with respect to the axis of the pivot pin, means in abutting relationship with and swingable with the coupler about the axis of said pivot pin, a projection carried by said swingable means arranged on a side of the pivot pin opposite the coupler, an arcuate end face on the projection generated about a vertical axis

5

laterally displaced with respect to the axis of said pivot pin whereby the end face of the projection is wedged into engagement with said buffing surface as the coupler is turned to an operative position.

3. In a coupler and pilot organization for a locomotive, a coupler including a shank, a pilot, vertically aligned bosses on the pilot, a vertically disposed pivot pin extending through the coupler shank into said bosses so that the coupler may be turned about the axis of the pin, a door structure abutting a rear end of the coupler shank mounted to turn about the axis of said pin with the coupler, a projection carried by the door structure arranged generally diametrically opposite the coupler shank, an arcuate end face on the projection generated about a vertical axis laterally displaced with respect to the center of said pivot pin, an arcuate buffing surface carried by the pilot struck about a vertical axis laterally displaced with respect to the center of the pivot pin whereby the end face of the projection is wedged into engagement with said buffing surface when the coupler is turned to an operative position to relieve the pivot pin of buffing forces in the application of pushing strains on the coupler, a guard arm on said coupler, and said buffing surface having a recess therein for receiving a portion of the guard arm when the coupler is in the retracted position.

4. In a pilot and coupler assembly, a pilot, vertically aligned bearings carried by the pilot, a coupler, a shank extending from the coupler, generally cylindrical shaped coaxial bosses at the rear end of the shank having an opening therethrough, a pivot pin extending through the opening in the coupler shank and into said bearings, a door structure having a vertically disposed channel therein arranged partly around and engaging the rear end of the coupler, a retaining member having a concave portion spanning one of the bosses on the rear end of the coupler shank, and means detachably securing the retaining member to said door structure.

5. In a pilot and coupler assembly, a pilot, vertically aligned bearings carried by the pilot, a coupler, a shank extending from the coupler, generally cylindrical shaped coaxial bosses at the rear end of the shank having an opening therethrough, a pivot pin extending through the opening in the coupler shank and into said bearings, a door structure having a vertically disposed channel therein arranged partly around and engaging the rear end of the coupler, a retaining member having a concave portion spanning one of the bosses on the rear end of the coupler shank, means detachably securing the retaining member to said door structure whereby the door structure and the retaining member may turn as a unit about the axis of said pivot pin, and a shelf on the retaining member supporting the coupler shank and movable with the door structure and the coupler.

6. In a coupler and pilot assembly for a locomotive, a pilot having a pocket therein, an inclined front face on the pilot sloping rearwardly in proceeding upwardly, a coupler including a shank connected to the pilot within the pocket for swinging movement about a vertical axis, a door structure secured to the coupler shank swingable about said vertical axis with the coupler so that the coupler may be retracted into the pocket and the door arranged forwardly of the coupler and substantially flush with respect to the inclined front face of the pilot, a projec-

6

tion carried by the door structure extending outwardly therefrom and arranged in substantially horizontal alignment with the coupler, and a substantially vertical end face on the projection adapted for engaging the coupler of another railway vehicle.

7. In a coupler and pilot assembly, a pilot having a pocket therein, an inclined face on said pilot, a coupler including a shank connected to the pilot for swinging movement about a vertical axis, a door structure secured to the coupler shank swingable with the coupler so that the door may be arranged forwardly of the coupler when the coupler is retracted into said pocket, means on the door structure providing an inclined surface flush with the inclined face of the pilot when the coupler is in the retracted position, a projection carried by the door structure extending outwardly from the inclined surface thereof and arranged in substantially horizontal alignment with the coupler, and a generally vertical end face on the projection in substantially horizontal alignment with couplers of other railway vehicles.

8. In a coupler and pilot assembly, a coupler having a shank, a pilot, means including a vertically disposed pivot pin connecting the coupler shank to the pilot so that the coupler may be turned in a horizontal plane, a fixed arcuate buffing surface carried by the pilot struck about a vertical axis displaced with respect to the axis of the pivot pin, means in abutting relationship and swingable with the coupler, a projection carried by said swingable means arranged on a side of the pivot pin opposite the coupler, an arcuate end face on the projection generated about a vertical axis laterally displaced with respect to the axis of said pivot pin whereby the end face of the projection is wedged into engagement with said buffing surface as the coupler is turned to an operative position, a vertically movable latch pin carried by said swingable means, and said pilot having a recess therein for receiving an end portion of the latch pin when the end surface of the projection firmly engages said buffing surface.

9. In a coupler and pilot assembly, a coupler having a shank, a pilot, means including a vertically disposed pivot pin connecting the coupler shank to the pilot so that the coupler may be turned in a horizontal plane, a fixed arcuate buffing surface carried by the pilot struck about a vertical axis displaced with respect to the axis of the pivot pin, means in abutting relationship and swingable with the coupler, a projection carried by said swingable means arranged on a side of the pivot pin opposite the coupler, an arcuate end face on the projection generated about a vertical axis laterally displaced with respect to the axis of said pivot pin whereby the end face of the projection is wedged into engagement with said buffing surface as the coupler is turned to an operative position, a vertically movable latch pin carried by said swingable means, said pilot having a recess therein for receiving an end portion of the latch pin when the end surface of the projection firmly engages said buffing surface, a block mounted for vertical movement on the swingable means adjacent said latch pin and forming an abutment for the coupler shank in its lower position, and a lug carried by the latch pin for engaging and lifting said block.

10. In a coupler and pilot organization for a locomotive, a coupler including a shank, a pilot structure, means including a vertically disposed

7

pivot pin connecting the coupler shank to the pilot structure so that the coupler may turn about the axis of said pivot pin and in a generally horizontal plane, a door structure abutting a rear end of the coupler shank and mounted to turn about the axis of said pivot pin with the coupler, a projection carried by the door structure arranged substantially diametrically opposite the coupler shank, a convex end face on said projection struck about a vertical axis offset from the center of said pivot pin to one side of a longitudinal center of the pilot structure, arranged transversely of the longitudinal center of the pilot structure whereby the convex end face on said projection is urged into firm contact with said
